CLAIM

The ornamental design of an intravenous equipment support or similar article, substantially as shown and described.

DESCRIPTION

FIG. 1 is a reduced perspective view of an intravenous equipment support or similar article showing our new design;

FIG. 2 is a side elevational view of the side opposite that is shown in FIG. 1;

FIG. 3 is a rear elevational view thereof with the bottom portion not being shown for ease of illustration; and
FIG. 4 is a top plan view thereof.

Fig. 1.

Fig. 3.

Fig. 2.
